REMOVABLE DISPLAY UNIT

Arthur B. Mull, Appleton, Wis., assignor to Marathon Paper Mills Company, Rothschild, Wis., a corporation of Wisconsin

Application September 1, 1936, Serial No. 98,981

3 Claims. (Cl. 40—124.1)

This invention relates to a display unit which can be removably attached to any suitable supporting surface.

One of the objects of this invention is to provide a display sheet carrying advertising matter thereon which can be conveniently affixed to any supporting surface or object.

Other and further objects and details of the invention will be apparent from the following descriptions and accompanying drawings, wherein

Figure 1 illustrates one embodiment of my invention suitable for use as a display card or price tag.

Figure 2 is a view of the display unit shown in Figure 1 provided with a cover strip in partially peeled condition.

Figure 3 is a perspective view illustrating one stage in setting up the display unit.

Figure 4 is a perspective view of the display unit in assembled condition.

Figure 5 is a side view of the display unit affixed to a supporting surface.

Figure 6 is a fragmental sectional view taken on line 6—6 of Figure 2.

Figure 7 is a sectional view taken on line 1—7 of Figure 5.

Figure 8 is a perspective view of another modification of the invention.

Figure 9 is a perspective view of another display unit made according to the invention.

Figure 10 is a sectional view taken on line 10—10 of Figure 8.

One embodiment of the invention is illustrated in Figure 1, wherein 10 indicates a display unit made of a stiff paper sheet or board. Any desired configuration may be given to the sheet depending upon the character of the advertising for which it is designed. The configuration illustrated in Figure 1 is adapted, for example,

40 for use as a price tag to be affixed to any desired article. One margin of the display unit is provided with a score line 12 spaced away from the edge to form a flange 11 when the unit is bent on the score line as shown in Figure 3. The score line 12 terminates in a short slit 13 extending to the upper edge of the display unit.

45 A short slit 14 is spaced inwardly from slit 13 at a distance approximately equal to the width of flange portion 11. A score line 16 is provided

50 at a suitable distance below the upper edge so as to form tabs 17 and 18. The flange portion 11 and tab 17 are coated on one face thereof with a pressure sensitive adhesive composition indicated by numeral 9. I prefer to use a hot melt pressure sensitive composition as disclosed in co-

pending application Serial No. 98,978. This composition consists essentially of a cohesive agent, an adhesive agent and a thermoplastic solvent therefor. The following composition is suitable for use on display units made of card- 5 board.

	Per cent by weight
Rubber	15
Vispronol	15
Amorphous paraffin wax (M. P. 155° F.)	19
Methyl abietate	25
Ester gum	25
Glycerine	0.5
Hydroquinone	0.5

The composition is preferably heated to about 180—200° F. and is applied to the base sheet by means of a roll or doctor blade heated to about 180—200° F. so as to spread a thin layer of the composition of suitable thickness on the base sheet. The base sheet is preferably supported 20 on a heated roll coating with the spreader roll and spaced away sufficiently to permit the desired thickness of coating to be applied. After the adhesive coating is spread it is congealed by 25 passing the web over a chilled roll and a cover strip is applied lightly thereto. This method and apparatus for carrying same out is disclosed in copending application Serial No. 98,978.

In order to protect the adhesive coating 9 applied on flange portion 11 and tab 17 prior to the use of the unit for attaching to any desired supporting surface, peable cover strip 15 is applied thereto. Such cover strip may be made of glassine, holland cloth, and the like which will 35 adhere to the adhesive coating but will readily peel therefrom.

In order to use the display unit illustrated in Figure 1, it is first necessary to assemble it in proper condition for affixing to the supporting 40 surface. In setting up the display unit, the cover strip 15 is first peeled from the margin or flange 11. The flange is then folded on score line 12 so as to be in a plane intersecting the plane of the display body 10 at about 90°. Tab 45 17 is then folded over as shown in Figure 3, at a right angle to flange 11. Tab 18 is then folded over tab 17 and applied thereto by pressure of the fingers. Inasmuch as tab 17 is coated with pressure sensitive adhesive it will retain the tab 50 18 in the position shown in Figure 4.

The display unit is now ready to be affixed to any suitable supporting surface by simply pressing with the thumb the adhesive coated face 9 55

of flange 11 against the supporting surface A as shown in Figures 5 and 7.

5 The display unit will remain firmly in place after being so attached, but it can be readily removed from the supporting surface by simply peeling it off without fouling or marring the supporting surface in any way.

10 The display unit may be made of any suitable sheet material such as cardboard, sheet metal, veneer, stiffened cloth, sheets made of synthetic materials such as celluloid, resins, and the like. It is obvious that any sheet material which may be printed or impressed with any indicia or to which any advertising matter may be affixed or 15 made integral therewith is contemplated within the scope of this invention. Any suitable shape, form or contour may be given to the display unit depending upon the purpose for which it is to be used.

20 An important advantage of the display unit made in accordance with the foregoing description is that both sides of the display unit are unobstructed and are visible after being attached to any supporting surface. Any advertising matter carried on both sides of the display unit is thus always visible to the eye as the body of the unit is spaced away from the supporting surface. The utilization of both faces of the unit and its spaced condition when attached thus gives the 30 unit great attraction value.

35 Figure 8 illustrates a modification of the display unit made in accordance with this invention. The unit consists of a body portion 20 of stiff cardboard printed with any suitable advertising matter. One margin of the unit is scored and slit in a manner similar to that shown in Figure 1 to provide a flange portion 21 and tab portions 22 and 23. Instead of applying the pressure sensitive adhesive directly to the flange 21 an adhesive strip is assembled separately and applied to the unit after it has been printed or otherwise ornamented for advertising purposes. This preformed adhesive strip consists of a base of paper tape or the like 27, coated on one face with a gum or 40 water soluble glue 28. The other face of the tape is coated with any suitable pressure sensitive adhesive 26 which is protected by a peelable cover strip 25, such as holland cloth or glassine. This unit is shown in partially separated condition in 45 Figure 8. The adhesive strip so assembled is applied to the flange 21 and tab 22 by moistening the gummed surface 28 and applying same to the unit as shown in Figure 8. The units are then distributed to the purchasers in this condition.

50 When the unit as shown in Figure 8 is to be attached to any desired supporting surface, the cover strip 25 is peeled off thereby exposing the pressure sensitive adhesive coating 26. The flange 21 is then bent at right angles to the body 20 of the unit and tab 22 folded over. Tab 23 is 55 then pressed over tab 22 which will be retained in position by the adhesive. The unit is then

attached to any supporting surface by merely applying the adhesive layer 26 to the supporting surface and pressing it with the fingers.

5 Figure 9 illustrates a display unit constructed similarly to the unit shown in Figure 1 except that the body portion is formed and printed to simulate a carton of cigarettes for display purposes. It is obvious that the flange construction herein disclosed may be utilized for displaying a great variety of objects made of paper, cardboard, metal foil, synthetically produced sheets and the like. The flange construction may be utilized, for example, to display paper cartons, cans, and similar light objects, by attaching them to any desired supporting surface.

10 15 It is obvious that many variations and changes may be made in the specific embodiment of the invention herein disclosed, and it is to be understood that all such variations are intended to be included in the appended claims as is broadly 20 consistent with the prior art.

I claim:

25 1. A display unit comprising a body portion, a flange portion coated with pressure sensitive adhesive for attaching the display unit to a supporting surface, said flange portion being provided with a tab portion coated with pressure sensitive adhesive, a second tab portion on the body portion of the display unit adapted to be folded over and adhered to said first tab for maintaining said flange at an angle to said body portion.

30 35 2. A display unit comprising a body portion, one margin of said body portion being provided with a score line to form a flange portion, a coating of pressure sensitive adhesive on said flange portion for affixing the display unit to a supporting surface, one end of said flange being provided with a tab portion disconnected from the body portion by a slit, a second slit in the body portion spaced from said first slit to provide a second 40 tab portion, the first tab being coated with pressure sensitive adhesive and adapted to retain the second tab folded thereover for retaining said flange at an angle to the body portion of the display unit.

45 50 3. A display unit comprising a body portion made of cardboard, one margin of said body portion being provided with a score line to form a flange portion, a coating of pressure sensitive adhesive on said flange portion for affixing the display unit to a supporting surface, a peelable cover strip on said adhesive coating, one end of said flange being provided with a tab portion disconnected from the body portion by a slit, a second slit in the body portion spaced from said first slit to provide a second tab portion, the first tab being coated with pressure sensitive adhesive and adapted to retain the second tab folded thereover for retaining said flange at an angle to the body portion of the display unit.

ARTHUR B. MULL. 60
